WELL BORE TREATMENT

Duke C. Matthews, Taylor, Tex.

Application June 27, 1938, Serial No. 216,111

2 Claims. (Cl. 166—21)

This invention relates to the art of well drilling, and particularly to the treatment of well bores at various stages of a drilling operation.

In the drilling of oil wells it often happens that 5 porous formations, or crevice strata, are encountered. Usually such formations or strata offer such low resistance to penetrating action of the well fluid or mud that the fluid is diverted from the well bore and is lost to an extent sufficient to 10 cut off or partially check proper circulation of the well fluid. Under such conditions it has been the practice in the art to seal off such formations or strata by introducing a well sealing compound into the bore and forcing it into the lateral area 15 to be sealed, so that proper circulation and drilling may be continued.

However, the sealing thus effected is of a permanent character, and is accordingly unsuitable to conditions in which the presence of oil or gas 20 is indicated or suspected in the crevice area or porous formation, and to which it is desired to set a well casing.

It is, therefore, an object of this invention to provide a method of temporarily plugging a crevice stratum or porous formation against loss of well fluid or cementing material while setting a well casing thereto, without permanently altering the physical character of the formation or stratum.

Under certain conditions of drilling it is desirable and necessary to make drill stem tests of crevices and porous formations, or to seat a casing at such crevices or formations. In such operations the presence of a drill stem or casing seat 35 is necessary, especially in large bores.

Accordingly, another object of the invention is to provide a method of temporarily blocking such crevices or porous formations against entry of a plastic setting material used in forming the required seat, without alteration or injury to the physical character of the formations or crevice areas.

Still another object is to provide a method of physically and temporarily sealing a well bore 45 crevice or porous formation by a soluble medium capable of only temporarily supporting at its surface a superimposed column of a plastic setting material, the physical character of the supporting medium changing automatically after the plastic setting material has hardened.

Other objects will be readily apparent to those skilled in the art.

In the accompanying drawings, wherein like characters of reference designate like parts throughout the several views:

Figure 1 is a vertical section through a well bore illustrating a step in the method of temporarily blocking off a porous formation or crevice while cementing a well casing.

Figure 2 is a similar view illustrating another step in the same method.

Figure 3 is a horizontal section taken on the line 3—3 of Figure 2.

Figure 4 is a vertical section through a well bore illustrating a step in the method of temporarily blocking off a porous formation or crevice while forming an artificial seat for a well casing or drill stem test.

Figure 5 is a similar view of a subsequent step in forming the seat.

Figure 6 is a similar view illustrating a further subsequent step in formation of the seat.

Figure 7 is a horizontal section taken on the line 7—7 of Figure 6.

In Figures 1 and 2 the well bore 8 has been 20 drilled to a stratum 9 which may be of porous character sufficient to permit ready seepage therethrough of the conventional well fluid, or which may contain lateral crevices 10, or both, and in which the presence of oil or gas is indicated or 25 suspected. Under such conditions the leakage of the well fluid impairs circulation and in many cases cuts it off entirely. Due to the possibility of encountering gas or oil it becomes necessary to case the well to that point, and in accordance with usual practice the casing must be cemented above the producing stratum. However, the porosity of the formation or the crevices would take up the cement unless sealed, but if permanently sealed the stratum may be rendered non-productive.

In the practice of the method of this invention the bottom of the well bore is filled from its bottom to a level above the top of the stratum 9 with a soluble compound pumped into the bore 40 through the drill stem. The compound employed is of the type disclosed in United States Patent No. 1,998,756 and is a product that may be obtained on the open market. It is soluble, and in its liquid form is pumped into the bore and 45 allowed to settle on the bottom where it soon forms a heavy, thick agglutinate mass 12 which fills the crevices 10 and seals the pores of the formation.

When the mass of agglutinate compound 12 has had time to thicken a casing 13 is run to a 50 point somewhere above the surface of the agglutinate, as shown in Figure 2, and cement is pumped down through the casing. When the agglutinate compound has thickened it becomes resistant to the passage of fluid and has a 55

strength amply sufficient to support the full weight of a column of the cement 14 or well fluid 15. In practice, the well fluid 15 is pumped following settling of the agglutinate 12 until free circulation is obtained, after which the casing 13 is run to the desired point. When the casing is in position the cement is pumped in and is forced up behind the casing as a column 14 supported directly on the top of the agglutinate sealing mass 12 or slightly thereabove in the event a small body of intervening fluid separates the cement from the sealing mass.

In those cases where the time for running a casing is short, the drill stem may first be removed and the casing run to the desired point, after which the agglutinate compound may be pumped down through the casing itself.

The compound 12 is of such character that it automatically liquefies after it has reached its maximum density. However, the liquefaction time is such that before the compound becomes sufficiently liquid to no longer support the column 14 the cement will have set and become fully hardened in situ.

Upon liquefaction of the compound 12 it is easily removable by pumping, and thus uncovers the crevices and pores of the stratum 8 which it has temporarily sealed. The physical character of the formation is unaltered by the temporary sealing, so that operations may be continued for bringing in the well if the stratum 8 is a producing level. If it proves not to be, the stratum may be sealed off in accordance with the conventional practice and the drilling may then be continued to lower depths.

The method of locating and forming an artificial seat for a well casing or a drill stem test is shown in Figures 4 to 7, in which the bore 8 has entered strata 9' of porous formation or containing crevices 10' through which the well fluid passes away or is absorbed so rapidly as to interrupt its proper circulation, and which would with equal facility absorb or divert cement.

As in the preceding method, the lower part of the well bore is filled with a mass of the agglutinating compound 12 until it rises to the top of the objectionable stratum or formation, being pumped in through the stem 11 and allowed to settle at the bottom of the bore. In due course the compound thickens to a density and consistency which effectively plugs up the crevices and pores of the formation, and which is of sufficient strength to support a column of cement 14' which is pumped into the well bore to a desired height.

The compound forming the agglutinate mass

12 automatically liquefies after reaching its maximum thickness, but before it liquefies to the point at which it is incapable of further supporting the weight of the cement column the cement will have set and become fully hardened in situ, forming a seat for a casing or for a drill stem test of the formation. The hardened cement body 14' forming the seat is then drilled to provide a bore 16 extending therethrough and through which the test can be made in the usual manner of such operations.

While certain specific applications of the method have been disclosed herein it is to be understood that the invention is capable of practice in other ways and for other purposes.

Having thus described the invention, what is claimed is:

1. In a well drilling operation, the method of forming a body of plastic setting material in situ in a well bore above an uncased portion into which such material would normally dissipate while in a plastic state; which comprises filling the bore throughout such portion with a liquefied compound which on standing forms into a thick agglutinate incapable of dissipation into said well bore portion and capable of supporting on its surface a body of the plastic setting material, and which subsequently resolves to liquid state after a longer time than the plastic setting material takes to set; and after the compound has thickened disposing on its surface a body of plastic setting material in a plastic state and allowing it to set into desired form.

2. In a well drilling operation, the method of cementing a casing above a porous formation or stratum which freely absorbs and dissipates well fluid and plastic cement, and which it is not desired to seal off, which comprises the steps of filling the well bore throughout such formation with a flowable compound which forms into a thick agglutinate incapable of dissipation into the formation and capable of supporting on its surface a body of cement and which subsequently resolves to liquid state after a longer time than the cement takes to set, placing a casing in the well bore with its lower end spaced somewhat above the surface of said compound, introducing cement through the casing onto the surface of the agglutinated compound and forcing the cement upwardly in the bore around the casing exterior, allowing the cement to harden in situ, and, when the agglutinate has resolved to liquid state, removing it from the well bore through the casing.
